UNITED STATES PATENT OFFICE.

GEORGE LEVI NICHOLS, OF DE KALB, ILLINOIS.

CATTLE-STANCHION.

SPECIFICATION forming part of Letters Patent No. 605,005, dated May 31, 1898.

Application filed December 16, 1897. Serial No. 662,147. (No model.)

To all whom it may concern:

Be it known that I, GEORGE LEVI NICHOLS, a citizen of the United States of America, residing at De Kalb, in the county of De Kalb 5 and State of Illinois, have invented certain new and useful Improvements in Cattle-Stanchions; and I do hereby declare the following to be a full, clear, and exact description of the invention, such as will enable others skilled 10 in the art to which it appertains to make and use the same.

My invention is an improvement in cattle-stanchions, the object of the same being to provide certain mechanism by which the movable stanchion-bars after being released assume an upright position parallel with the stationary bars and are automatically locked by a series of pivoted bails which are released by a shifting-rod that also serves to move the 15 pivoted stanchion-bars simultaneously to an inclined position, including devices which automatically engage the pivoted bars when thrown to an inclination, said devices being susceptible of operation to release said bars 20 either independently or collectively.

The particular construction and arrangement of the instrumentalities for attaining the above objects provide for accomplishing the several operations in a positive and effective manner.

The following specification enters into a detail description of my invention, reference being made to the several parts by letters, and what I claim to be new and desire protection upon is more particularly set forth in the appended claims.

In the accompanying drawings, forming part of this specification, Figure 1 is a front elevation of my improved cattle-stanchion. 40 Fig. 2 is a plan view. Fig. 3 is a sectional view on the lines 3-3 of Fig. 1.

A A designate longitudinal base-pieces, between which are rigidly secured at intervals upright stanchion-bars B B and end post B', connected and braced to each other at their upper ends by horizontal beams C C, these parts forming the rigid framework of the stanchion. Pivoted between the base-pieces A A at the usual distance from each stationary stanchion-bar B are a set of movable stanchion-bars D, guided at their upper ends by the beams C C, between which they move,

the extreme upper end of each being beveled toward the adjoining bar, for the purpose hereinafter explained. The movable stanchion-bars are drawn toward the stationary bars by helical springs d, the movement in this direction being limited by cross bars or stops c, positioning the former bars parallel with the latter bars, while the movable bars 60 are held at an inclination against the action of said springs by pins e, playing in an opening through the forward beam C and carried by a lever-section E, connected to a second lever-section E, said lever-sections being pivoted to brackets c, projecting from the aforesaid beam. A flat spring F bears against this sectional lever, acting to automatically operate the same to move the pin e in position to engage the movable stanchion, the 65 said lever being operated against the action of the spring by means of a bent lever E², pivoted in a bracket b, secured to the stationary stanchion-bar. It will be here noted that the movable stanchion-bar should be of a 70 width to hold the movable stop-pin retracted when said bar assumes its closed position, for it is obvious that when the bar is shifted to its inclined position it is moved beyond the pin, permitting the latter to be actuated by 75 the spring. When a narrow stanchion-bar is employed, a plate d' is attached thereto, as shown, to provide for the proper engagement with the movable stop-pin, said plate being extended across the bar to prevent wear by 80 contact of the pin directly therewith.

Between each set of movable and stationary stanchion-bars upon the longitudinal beams C C is pivoted a bail H, which projects toward the movable bar and automatically 85 engages therewith, being lifted by riding upon the beveled end of said bar, an excessive movement of the bail being prevented by the extended ends h, which are bent as shown.

It is apparent that the movable stanchion-bars could be tilted or moved away from the stationary bars independently by hand to bring them into an operative position, and also that the pivoted bails, which lock said bars in a closed position, could also be operated directly by hand; but in order that these two operations may be accomplished simultaneously and by the movement of a single lever I have devised certain mechanism for

the purpose, which shall be now described, said mechanism also serving to release the bars in unison, as hereinafter explained.

- I designates a horizontal rod located below the front beam C and having a sliding movement in eyes *h* at the lower ends of vertical rods K, guided in staples *c*², driven into the aforesaid beam, the upper end portions of said rods being bent under the free ends of the bails II and extended upward therefrom and the terminals bent at an angle to limit the upward movement of said bails in place of the other construction, hereinafter described, for the same purpose, whichever preferred. The sliding rod I is provided with inwardly-projecting arms *i*, adapted to engage the inner side of the movable stanchion-bars D and move said bars by the shifting of said rod. By this arrangement a longitudinal movement of the sliding rod opens the stanchion, while a vertical movement, carrying the vertical rods K with it, will lift the locking-bails II out of engagement with the movable stanchion-bars, and in order to accomplish this last operation automatically and at the proper time the sliding rod is guided by rails L, secured to the front beam C and presenting an inclined portion connecting with a horizontal portion. The sliding rod is operated by a bent lever M, fulcrumed in a bracket *b*', secured to the post B', the lower end of said lever being bent outward to form a handle *m*, the lever carrying a pawl or dog *n*, pivoted thereto and adapted to engage a segment-rack N, secured to post B'. When it is desired to release the movable stanchion-bars simultaneously or independently of the sectional levers, which carry the movable stop-pins, the pawl is brought into engagement with the rack before said lever has been manipulated to the extent of moving the stanchion-bars, through the intervention of the sliding rod and arms, clear of the stop-pins, so holding the stanchion-bars that they can all be released simultaneously by simply moving the pawl out of engagement with the rack. It will be seen, therefore, that it is possible to operate and hold the movable stanchion-bars entirely by means of the lever M and pawl and ratchet at one end of the stanchion-frame without requiring the operator to move from his position at this point.

From the foregoing description, in connection with the accompanying drawings, the construction, operation, and practical advantages of my improved cattle-stanchion will be readily apparent, for the mechanism provides an arrangement by which the stanchion-bars can be actuated either simultaneously or independently, and the particular construction insures a positive movement of all the operative parts to effectually accomplish the purposes of the invention.

Having thus described my invention, I claim—

1. In a cattle-stanchion, the combination

with the stationary and movable bars, and means for moving the latter toward the former, of stops limiting this movement, sliding stop-pins for holding the movable bar at an inclination with respect to the stationary bar, and a bail engaging the movable bar when the same is moved into position closing the stanchion, substantially as shown and described.

2. In a cattle-stanchion, the combination with the stationary and movable bars, and means for moving the latter toward the former, the movable bar having a beveled upper end, of sliding stop-pins for holding the movable bar at an inclination with respect to the stationary bar, and a pivoted bail adapted to ride over the end of the movable bar and engage the same, substantially as shown and described.

3. In a cattle-stanchion, the combination with the stationary and movable bars and means for moving the latter toward the former, the movable bar having its upper end beveled, of sliding stop-pins engaging the movable bar to hold the same at an inclination with respect to the stationary bar, means automatically moving the stop-pin into such engagement, and a pivoted bail adapted to ride over the end of the movable stanchion-bar and engage the same, substantially as shown and described.

4. In a cattle-stanchion, the combination with the stationary and movable bars and means for moving the latter toward the former, the movable bar having its upper end beveled, means for engaging and releasing the movable bar, and a pivoted locking-bail adapted to ride over the end of the movable bar and engage the same, the ends of said bail being extended and bent to limit its upward movement, substantially as shown and described.

5. In a cattle-stanchion, the combination with the stationary and movable bars and means for moving the latter toward the former, of a sliding stop-pin engaging the movable bar to hold the same at an inclination with respect to the stationary bar, a pivoted lever connected to said stop-pin, and a spring moving the stop-pin into engagement with the movable stanchion-bar; together with means for locking said stanchion-bar in a closed position, substantially as shown and described.

6. In a cattle-stanchion, the combination with the stationary and movable bars and means for moving the latter toward the former, of a sliding stop-pin engaging the movable bar to hold the same at an inclination with respect to the stationary bar, a lever consisting of two pivoted sections connected to each other, one of the sections being connected to the stop-pin, an operating-lever engaging the other section, and a flat spring bearing against the sectional lever to project the stop-pin into engagement with the stanchion-bar; together with means for locking

said stanchion-bar in a closed position, substantially as shown and described.

7. In a cattle-stanchion, the combination with the stationary and movable stanchion-bars and means for moving the latter toward the former, bails engaging the movable bars when closed, a sliding rod engaging said movable bars to move them away from the stationary bars, the rod having a vertical movement, rods connected to said sliding rod and engaging the bails, and means for holding the sliding rod, substantially as shown and for the purpose set forth.

8. In a cattle-stanchion, the combination with the stationary and movable bars and means for moving the latter toward the former, the movable bars having their upper ends beveled, of bails engaging the upper ends of the movable bars, a sliding rod having arms which engage said movable bars to move them away from the stationary bars, and means actuated by the sliding rod to lift the bails out of engagement with the stanchion-bars, substantially as shown and for the purpose set forth.

9. In a cattle-stanchion, the combination with the stationary and movable bars and means for moving the latter toward the former, of bails engaging the upper ends of the

movable bars, a sliding rod having arms 30 which engage the movable bars to move them away from the stationary bars, guide-rails engaging the arms to move the sliding rod vertically, and means actuated by the vertical movement of the sliding rod to lift the locking-bails, substantially as shown and for the purpose set forth.

10. In a cattle-stanchion, the combination with the stationary and movable bars and means for moving the latter toward the former, of bails engaging the upper ends of the movable bars, a sliding rod having arms which engage the movable bars to move them away from the stationary bars, guide-rails engaging the arms to move the sliding rod vertically, 45 rods connected to the sliding rod and engaging the locking-bails, being extended above the same, a lever for operating the sliding rod, a pawl pivoted to the lever, and a rack-bar with which the pawl engages, substantially as shown and for the purpose set forth.

In testimony whereof I affix my signature in presence of two witnesses.

GEORGE LEVI NICHOLS.
